UNITED STATES PATENT OFFICE.

AMOS P. STEINER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA.

DOG FOR GRINDING MACHINES.

Application filed June 20, 1924. Serial No. 721,290.

My said invention relates to a trip or dog intended primarily for use in grinding machines where a reciprocating element acts on a reversing lever to change the direction of travel of a reciprocating carriage at predetermined intervals. In the present instance such a reversal occurs after four strokes of the carriage in each direction and the reversal is preceded by a slow additional movement in the direction of the last stroke as more fully explained in my co-pending application No. 721,292 of even date herewith.

Referring to the accompanying drawings which are made a part hereof and on which similar reference characters indicate similar parts,

Figure 1 is an elevation of my invention in a preferred form thereof,

Figure 2, a section on line 2—2 of Figure 1,

Figure 3, a detail of a part illustrated in Fig. 1, and

Figure 4, an elevation of a device partially shown in Figure 1.

In the drawings reference character 10 indicates a part of a rack used in certain types of grinding machines said rack having oblique teeth at its upper side meshing with a worm 11 by means of which the dog 12 can be adjusted bodily along the rack. The dog includes a vertically movable slide 13 normally held down by a spring 14 in a position to engage a block 15 shown in dotted lines in Figure 1, said block forming part of a reversing lever for the driving mechanism of the traversing carriage and said slide normally serving to move the lever in one direction.

The dog also embodies a cam 16 engaging underneath a follower on the slide 13 or which may be located between depending legs on the slide or otherwise arranged to lift the slide. The cam is fixed to a ratchet 17 here shown as having four teeth. As the dog reciprocates with the carriage of the grinding machine the teeth are brought successively into the field of operation of a

stationary pawl 18 here shown as pivoted at 19 on a horizontally adjustable support 20. A spring 21 is secured at one end to a bolt 22 projecting from the support 20 to which it is adjustably secured and said spring at its other end is attached to an upwardly extending arm 23 integral with the pawl 18. It will be seen that as the dog reciprocates the pawl engages successively with different teeth and must swing downward to pass the teeth of the ratchet which necessitates the pivotal mounting or some equivalent arrangement.

A spring actuated detent 24 is supported on the front plate of the dog and is adapted to engage in any one of a series of depressions 25 on the cam for holding said cam and the ratchet against accidental displacement.

To the right of the ratchet or to the rear of the slide in the direction of operation of the dog there is another slide 26 squared at its lower end and guided by means of a slot 27 cooperating with a pin 28 projecting through the front plate. A spring 29 surrounding a reduced part of the latter slide bears at one end against a fixed part of the dog and at the other end against a shoulder on the slide 26. A head 30 on the slide limits its downward movement and serves as means by which the slide may be lifted when it is desired to have the lower end of the slide pass over the block 15 without engagement therewith.

In the operation of my device the dog travels from the position shown in Figure 1 toward the right as indicated by the arrow 31, the vertical line at the end of the arrow indicating the farthest position of the axis of the shaft 32 which forms the pivot of the cam and the ratchet and which also coacts with a slot 33 in the slide 13 for guiding the slide and supporting it in place. When the dog reaches its limit of movement as above described one of the teeth 17 will have been engaged by the pawl 18 and the ratchet will have been rotated through an arc of 90 degrees which may of course be varied for a different number of strokes of the recipro-

cating element as desired. Assuming the tooth first engaged to be the one corresponding to the lowest part of the cam the slide 13 will now have been raised a short distance by the cam. At each succeeding stroke toward the right the slide will be raised until at the fourth stroke it is high enough to pass over the block 15 whereupon the dog and the carriage supporting it will continue to move to the left until the reversing lever is thrown by means of the flattened lower end of slide 26. On the ensuing stroke of the carriage toward the right the pawl 18 will engage the tooth corresponding to the high part of the cam 16 and will move the cam so far that the slide 13 will ride off the high part of the cam and return to the lowest part of the same whereupon the sequence of operations will be resumed.

20 The lower ends of the slides provide movable abutments for actuating a device here indicated as a reversing lever, but which might be any other device which is to be moved at intervals. The abutments may 25 also be varied in shape and other details. It will be obvious to those skilled in the art that many other changes may be made in my device without departing from the spirit of the invention and therefore I do not limit 30 myself to what is shown in the drawings and described in the specification, but only as indicated in the appended claims.

Having thus fully described my said invention, what I claim as new and desire to 35 secure by Letters Patent is:

1. In combination, a reversing lever and an actuating dog therefor said members having relative reciprocatory movement, an element on the dog slidably transversely of the 40 line of such movement, a cam, and means for moving the cam on successive reciprocatory movements to move said slidably element out of the path of the reversing lever, substantially as set forth.

45 2. A reversing dog comprising a slide adapted to engage a reversing lever in one position, a cam engaging said slide, a ratchet concentric with and fixed to said cam, and a stationary pawl adapted to engage the ratchet on successive movements of the carriage in one direction, substantially as set forth.

50 3. A reversing dog comprising a vertically movable slide normally adapted to engage a movable device during a movement of translation of the dog, a spring normally holding the slide in its lowest position, a cam for raising it, and means for moving the cam step-by-step toward its highest position, substantially as set forth.

55 4. In combination, a reversing lever, a reversing dog, a slide on the dog adapted to engage and actuate the reversing lever, a spring normally holding the slide in engaging position, a cam for moving the slide out

of such position, and pawl and ratchet mechanism for moving the cam through successive cycles to move the slide automatically out of such engaging position and thereafter release it, substantially as set forth.

5. A reversing dog comprising a vertically movable slide adapted to engage a reversing lever, a spring normally holding the slide in its lowest position, a cam for lifting the slide, pawl and ratchet mechanism for moving the cam through successive cycles to raise the slide automatically and thereafter release it, and an abutment on the dog adapted to engage the reversing lever after said slide has passed the normal engaging position, substantially as set forth.

6. A reversing dog comprising a vertically movable slide adapted to engage a reversing lever, a spring normally holding the slide in its lowest position, a cam for lifting the slide, pawl and ratchet mechanism for moving the cam through successive cycles to raise the slide automatically and thereafter release it, an abutment on the dog adapted to engage the reversing lever after said slide has passed the normal engaging position, and means whereby said abutment may be moved out of the path of the reversing lever, substantially as set forth.

7. A reversing dog comprising a vertically movable slide adapted to engage a reversing lever, a spring normally holding the slide in its lowest position, a cam for lifting the slide, pawl and ratchet mechanism for moving the cam through successive cycles to raise the slide automatically and thereafter release it, an abutment on the dog adapted to engage the reversing lever after said slide has passed the normally engaging position, means whereby said abutment may be moved out of the path of the reversing lever said abutment having a flat face for engaging the lever, and means to insure engagement of said flat face with the lever, substantially as set forth.

8. In combination, a lever, a dog having relative to and fro movement past the lever, a slide on the dog for actuating said lever, manual means for moving the slide out of actuating position, a spring for normally holding the slide in actuating position, a flat face at the lower end of the slide for engaging said lever, and means to prevent rotation of the slide, substantially as set forth.

9. A log adapted to be attached to an element of a machine, an abutment on the dog normally positioned to strike another element of such machine, having reciprocatory movement relatively to the first element, and means controlled by such relative movement for intermittently removing said abutment step-by-step out of engaging relation with said second element, substantially as set forth.

10. A device as in claim 9, with means for

automatically returning said abutment to such engaging relation, substantially as set forth.

11. A dog adapted to be attached to a movable element of a machine, an abutment on the dog normally positioned to move another element of such machine, means controlled by the movement of the first-named element for intermittently removing said abutment out of engaging relation with said

second element, and a second abutment on the dog adapted to engage said second element when the first dog is out of such engaging relation, substantially as set forth.

In witness whereof, I have hereunto set my hand and seal at Waynesboro, Pennsylvania this 17th day of June, A. D. nineteen hundred and twenty-four.

AMOS P. STEINER. [L.S.]
